Primary Examiner—Caron Veynar*Assistant Examiner*—Abraham Bahta(74) *Attorney, Agent, or Firm*—Mark D. Perdue; Storm LLP(57) **CLAIM**

The ornamental design for a retail merchandising unit base, as shown and described.

DESCRIPTION

FIG. 1 is a side view of a retail merchandising unit base showing our new design;

FIG. 2 is a side view, in which the retail merchandising unit base is rotated 180° from the position of FIG. 1;

FIG. 3 is a side view, in which the retail merchandising unit base is rotated 90° counterclockwise from FIG. 1;

FIG. 4 is a side view of the retail merchandising unit base rotated 90° clockwise from FIG. 1;

FIG. 5 is a top view thereof;

FIG. 6 is a bottom view thereof;

FIG. 7 is an isometric view thereof; and,

FIG. 8 is an isometric view of FIG. 2 in which the lower shelf is removed for ease of illustration.

It will be understood that shading presented in the drawings is for illustration only, and does not form part of the claimed design. Furthermore, it will be understood that the elements illustrated by broken lines are for illustration only, and do not form part of the claimed design.
